Primary Examiner — David G Muller*Assistant Examiner* — Nathan M Johnston(74) Attorney, Agent, or Firm — Tutunjian & Bitetto, P.C.(57) CLAIM

The ornamental design for the barrel plant stand, as shown and described.

DESCRIPTION

FIG. 1 is a perspective view of a barrel plant stand showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines represent portions of the barrel plant stand that form no part of the claimed design.

1 Claim, 7 Drawing Sheets(56)
